G. A. SMITH

CRUDE OIL BURNER

Original Filed July 18, 1921

FIG. 1

FIG. 3

FIG. 4

FIG. 5

FIG. 2

INVENTOR:

George Arbuthnott Smith

BY

Pierre Barnes

ATTORNEY

UNITED STATES PATENT OFFICE.

GEORGE ARBUTHNOTT SMITH, OF OCEAN PARK, CALIFORNIA.

CRUDE-OIL BURNER.

Application filed July 18, 1921, Serial No. 485,532. Renewed December 27, 1923.

To all whom it may concern:

Be it known that I, GEORGE ARBUTHNOTT SMITH, a subject of the King of England, residing at Ocean Park, county of Los Angeles, 5 and State of California, have invented certain new and useful Improvements in Crude-Oil Burners, of which the following is a specification.

This invention relates to hydrocarbon 10 burners and more especially to crude-oil burners.

Its object is to produce a simple and inexpensively constructed device of this character which is adapted to be conveniently 15 employed within an ordinary cooking stove, which is economical in the consumption of fuel and which is absolutely safe.

With these ends in view, the invention consists in the novel construction, arrangement 20 and combination of parts hereinafter described and claimed.

In the accompanying drawings,—

Figure 1 is a longitudinal vertical section of a burner embodying my invention shown 25 in its preferred form and applied to a stove. Fig. 2 is a plan view of the burner shown in Fig. 1. Fig. 3 is a transverse vertical section of a burner shown in a modified form, said section being taken through 3—3 of Fig. 30 4. Fig. 4 is a plan view of Fig. 3 and Fig. 5 is a perspective view of the burner illustrated in Figs. 3 and 4.

In said drawings, the numeral 5 designates 35 a cooking stove having a fire box 6 and the usual holes, such as 7, in its top 8.

In carrying out my invention I provide a shallow pan 9 of a diameter less than that of the stove hole 7 to permit its being inserted therethrough. Said pan is of the 40 shape of an inverted truncated cone and is desirably provided about its upper edge with a flange or brim 10. Secured in circumferentially spaced relations to the pan are hangers 11 which depend from a plate 12 of greater 45 diameter than the hole 7 and is supported upon the stove top 8. Said plate constitutes the cover for said hole and the roof member of the burner.

The plate member in the preferred construction, Figs. 1 and 2, is of a truncated conical form with a marginal rim 13 which seats against the upper surface of the stove top.

An aperture 14 is provided in the plate 50 member 12 through which fuel oil is poured into the pan for starting a fire or to replenish

the same when in operation. Said aperture also affords a means for applying a flame of fire into the burner to start the burning of the fuel.

Air for combustion purposes is admitted into the interior of the burner through draft openings 15 provided in the sloping peripheral wall 16 of the roof member 12.

In the modified form, see Figs. 3, 4 and 5, the roof member 12¹ is in the nature of a plane plate having a substantially rectangular shape with a length and width somewhat greater than the diameter of the stove hole 7 and, similar to the member 12, is provided 70 with a centrally disposed fuel supply aperture 14¹.

18 represents a slot provided in the plate 12¹ to accommodate a stove lifter of any well known type. In each of the illustrated embodiments of the invention, the pan 9 is disposed at a short distance below the respective plate so that the heat produced by burning oil in the pan will render the plate extremely 80 hot for cooking and will serve to direct the flames against the stove top.

For operation a layer of porous material such as coal ashes or sand is advantageously placed in the pan and a small quantity of oil 85 poured thereupon through the aperture 14. A convenient way to ignite the oil is to deposit a burning piece of oil-saturated paper through said aperture. When the oil in the pan burns it produces a fire which may be promoted or decreased by regulating a 90 damper, not shown, in the smoke pipe 19 of the stove or, where a plane plate is employed as illustrated in Figs. 3 and 4, by shifting the burner horizontally so that the plate 12¹ will leave a draft opening of suitable size 95 through the hole 7 at one side of the plate to admit air into the fire box for combustion purposes.

The pan by being suspended adjacent to the plate affords a combustion chamber between the plate and the pan with a relatively small opening above the brim thereof for the intake of air to combine with the oil vapors and for the escape of the hot combustion gases principally in the form of flames. The 100 heat produced by the burning oil gases in the pan is sufficient to maintain the temperature therein considerably above that requisite for combustion. When the fire becomes low additional fuel oil may be poured through the 110 aperture 14 without any danger to the operator.

What I claim, is,—

1. An oil burner, comprising a pan open at the top, a plate of greater diameter than the pan, said plate being of a substantially truncated conical shape, and means rigid with and depending from said plate to support the pan in parallel relations therewith and afford an intervening space, said plate being provided with an oil-feed aperture located in approximately the axis of the pan, and with draft openings in the peripheral wall thereof.
2. In apparatus of the character described, the combination with a fire-box having a top wall with a hole therein, of a burner com-

prising a truncated conical shaped plate adapted to seat upon said top wall at diametrically opposite sides of the hole, said plate having draft openings in the sloping peripheral wall thereof, a pan, and hanger elements secured to said plate and extending through said hole to support the pan within the fire-box. 20

Signed at Seattle, Washington, this 6th day of July, 1921.

GEORGE ARBUTHNOTT SMITH.
